DESIGN FOR A VAPORIZER

David Chapman, Chicago, Ill., assignor to Hanks-craft Company, Madison, Wis., a corporation of Wisconsin

Application October 18, 1947, Serial No. 142,009

Term of patent 14 years

(Cl. D83—1)

To all whom it may concern:

Be it known that I, David Chapman, a citizen of the United States, residing at Chicago, in the county of Cook and State of Illinois, have invented a new, original, and ornamental Design for a Vaporizer, of which the following is a specification, reference being had to the accompanying drawing, forming a part thereof.

In the drawing,

Fig. 2 shows a top plan view of the vaporizer illustrated in Fig. 1; and

Fig. 3 shows an end elevation of the vaporizer looking toward the right as viewed in Fig. 1.

I claim:

The ornamental design for a vaporizer, as shown.

DAVID CHAPMAN.
